(57) **CLAIM**

We claim the ornamental design for a display board, as shown and described.

DESCRIPTION

FIG. 1 is a perspective view of a display board embodying the present invention.

FIG. 2 is a front view of the display board.

FIG. 3 is a right side view of the display board.

FIG. 4 is a left side view of the display board.

FIG. 5 is a top view of the display board; and,

FIG. 6 is a bottom view of the display board.

The broken lines showing the two rectangular features on the front in FIGS. 1 and 2, and the support structure on the upper rear in FIG. 1 and FIGS. 3-6, and the inside in FIGS. 3 and 4 are included for the purpose of illustrating environment and form no part of the claimed design.
